UNITED STATES PATENT OFFICE.

RAYMOND A. HEISING, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING.

Application filed September 29, 1919. Serial No. 327,099.

To all whom it may concern:

Be it known that I, RAYMOND A. HEISING, a citizen of the United States, residing at East Orange, in the county of Essex, State 5 of New Jersey, have invented certain new and useful Improvements in Signaling, of which the following is a full, clear, concise, and exact description.

This invention relates to transmission systems and more particularly to high frequency signaling transmission systems.

The general object of the invention is to provide more efficient and selective and therefore improved means for and methods 15 of transmission by high frequency waves. The means and methods outlined are more particularly adapted for wireless telephony, but the principles of the invention are also applicable to telegraphy and telephony 20 either with or without wires.

A particular object is the provision of improved means for multiplex or other communication systems whereby interference due to certain parasitic and undesirable 25 waves of certain frequencies is eliminated.

A further object is the provision of means whereby electromagnetic waves of certain components are transmitted, which waves produce at a receiver the useful effects which 30 would be produced by a plurally modulated wave without causing interference with other signaling systems to the same extent as is often true in the case of the transmission of plurally modulated waves.

The invention has for a further object to produce a wave having certain characteristics of a plurally or successively modulated wave without performing the operation of plural or successive modulation.

Further objects will be apparent to those skilled in the art from a perusal of the following detailed description.

In the accompanying drawings, Fig. 1 illustrates diagrammatically the wave lengths transmitted by a plural or a successive modulation system where the harmonics of the intermediate frequency are present; Figs. 2 to 5 inclusive represent transmission systems involving the principles of the invention; Fig. 6 is a simple form of receiving system adapted to receive messages from such systems as shown in Figs. 2, 3 and 4; Fig. 7 is a form of receiving system adapted for receiving a plurality of messages such as can be transmitted by means

of the system of Fig. 5; and Fig. 8 illustrates a system comprising a plurality of transmitting and receiving stations, one only of the transmitting stations being provided with means to transmit an unmodulated carrier wave which may be utilized at each of the receiving stations.

Suppose it is desired to transmit with certain known types of systems a plurally modulated wave, that is, a wave of carrier 65 frequency p which has been modulated in accordance with a supplemental carrier wave of frequency q , the supplemental wave of frequency q being already modulated in accordance with a signaling wave of frequency s where s represents, in the case of telephony, the frequencies necessary for the reproduction of speech. As shown in Fig. 1 waves would be transmitted having the frequencies p , $p+q$, and $p-q$, also the bands of 70 frequencies $p+q \pm s$ and $p-q \pm s$. Since, however, with practical forms of generators there will always be present a greater or less portion of harmonics of the frequency q which may be designated q_1 , q_2 , etc., additional frequencies and bands of frequencies 75 will be transmitted as shown in Fig. 1. This necessarily results in confusion between stations and between the various messages of one and the same station where 80 multiplexing is carried out by using a plurality of supplemental carriers q each having a different frequency and each being modulated in accordance with one or more signals. By means of the systems herein 85 described the harmonics of the supplemental carrier wave of frequency q will be eliminated and any other harmonics introduced will be far out of the working range 90 of the frequencies being transmitted. Furthermore, the side band which includes one of the sets of frequencies $p-q$ and $p-q \pm s$ or $p+q$ and $p+q \pm s$ may be eliminated if desired.

In Fig. 2 a wireless transmission system is 100 shown which is adapted to produce and radiate a wave of frequency $p=500,000$ and a modulated wave of frequency $p+q \pm s = 550,000 \pm s$. The oscillator O comprises any suitable means and is herein represented as a thermionic vacuum tube suitably connected to a circuit arrangement to generate oscillations of the frequency of 500,000 cycles per second. These oscillations are impressed 105 upon the input circuit 1 of an amplifier sys- 110

tem A of any suitable type, but herein illustrated as a thermionic repeater system. Also impressed on the circuit 1 are waves of a frequency of 550,000 cycles which are generated by the thermionic oscillation system O'. The oscillator O' is associated with any suitable means for causing its oscillations to be modulated in accordance with signals. In the present instance this is accomplished 10 by placing the anode-cathode circuit of the vacuum tube 3 of the oscillator O' in shunt to the anode-cathode circuit of vacuum tube 4, whose impedance is varied in accordance with waves of signaling frequency in the 15 microphone circuit 5. A common source 6 supplies space current to tubes 3 and 4 through the speech frequency choke coil 7. The amplifying system A impresses upon the antenna system 7 the waves impressed 20 upon its input circuit by the oscillators O and O'. The system 7 typifies any suitable type of radiating or other transmitting circuit.

Referring to Fig. 3 the oscillator O functions in a manner similar to the corresponding oscillator in Fig. 2. In addition to the oscillator O' another oscillation generating system O'' is provided. The set of vacuum tubes 4, to whose input circuit is connected 25 the source 5 of the signals to be transmitted, is connected to each of the oscillation generators O' and O'' so that the oscillations of each may be modulated in accordance with the same signal. The means provided for 30 accomplishing this result consists of the common source 6 and a choke coil 7' functioning as in the arrangement of Fig. 2. Keys 8, 9 and 10 are provided. When the key 8 is opened the oscillator O ceases to impress 35 oscillations upon the input circuit 1 and when the keys 9 or 10 respectively are opened the generators O' and O'' cease to generate oscillations. The amplifying system A and the transmission line 7 function to transmit 40 whatever waves are being generated by the oscillators O' and O''.

In Fig. 4 the sources 11 and 12 produce unmodulated oscillations having frequencies of 550,000 and 450,000 cycles per second respectively. The source 12, however, may be adjusted to generate oscillations having a frequency of 500,000 cycles per second for the reason hereinafter mentioned. The oscillations so produced by the sources 11 and 50 12 are impressed upon the input circuit 13 of a thermionic amplifier 14 whose anode-cathode path is in parallel with the anode-cathode path of a thermionic device 15 with respect to source 16 and the speech frequency 55 choke coil 18. To the input circuit 19 of the device 15 is connected any suitable source 20 such as a microphone circuit or telephone line. The impedance of the device 15 will be varied in accordance with signaling waves in 60 the circuit 20 which will cause a correspond-

ing variation in the amplifying power of the device 14. By this means the waves from the source 11 and 12 will be impressed upon the antenna system 7 and transmitted as modulated high frequency waves. 70

The arrangement of Fig. 5 is, in general, similar to that of Fig. 2. Additional oscillators O' are, however, provided, having frequencies of 540,000, 530,000, 520,000 and 510,000 cycles per second respectively. 75 Means are provided similar to those shown in connection with Fig. 2 for causing the wave at each oscillator to be modulated in accordance with a signal individual thereto. All the waves generated are impressed upon 80 the input circuit of the amplifier system A and radiated by the transmission circuit 7.

The circuit illustrated in Fig. 6 is adapted to receive waves sent out from transmitting systems such as shown in Figs. 1, 2, 3 and 4. 85 The system is also adapted to selectively receive one of the high frequency signaling waves transmitted by the system in Fig. 5. The receiving system comprises a suitable receiving conductor 21 coupled to a tuned circuit 22 which will in general be tuned to the mean frequency of the waves to be received. The circuit 22 is in the input circuit of a detector 23 whose output circuit includes a tuned circuit C to which is connected 90 a similar circuit D, which in turn is included in the input circuit 24 of a second detector 25 whose output circuit comprises a telephone receiver or other suitable indicating instrument 26. 95

In receiving waves from a system such as shown in Fig. 2 the wave having a frequency of 500,000 cycles per second and the modulated wave of 550,000 cycles per second are impressed upon detector 23, thereby producing in the circuit C a wave having as one component a frequency of 50,000 cycles. The 50,000 cycle wave corresponds to the intermediate or auxiliary carrier wave in a plurally modulation system. Thus it is seen 100 that although this auxiliary wave is not generated at the transmitter the same effect is produced at the receiver as if it were being generated at the transmitter. The circuits C and D represent any suitable selective circuits to filter interfering waves from the auxiliary carrier wave. This wave will be modulated in accordance with whatever signaling wave is present in the circuit 5 at the transmitter and upon detection by the detector 25 the corresponding signal will be reproduced in the device 26. 110

The arrangement illustrated in Fig. 3 may be used to transmit in several different ways. If one only of the oscillators O' and O'' is 125 operating and the oscillator O is idle, then the wave transmitted will be an ordinary modulated wave and may be received by a system comprising a single detector. If both the oscillators O' and O'' are operating, a 130

system such as Fig. 6 may be used to receive the resulting signaling wave either by tuning the circuits C and D to select a wave having a frequency of 100,000 cycles or by applying 5 from a local source 27 to the input circuit of detector 23 a wave having a frequency of 500,000 cycles. In this case the circuits C and D would be tuned to select a wave of 50,000 cycles. This signal could, however, 10 be detected by a single detector having selective circuits for receiving a wave of 450,000 cycles or 550,000 cycles. If the generator O is operating and either or both of the generators O' and O'' are operating, 15 then the arrangement of Fig. 6 may be used to receive by tuning the circuits C and D to select an auxiliary carrier frequency wave of 50,000 cycles.

The receiving system illustrated in Fig. 7 20 is similar to that shown in Fig. 6 except that additional sets of tuned circuits C', D', C'', D'', etc., are provided. These circuits will be arranged to select auxiliary carrier frequency waves of 50,000, 40,000, 30,000, 20, 25 000 and 10,000 cycles respectively corresponding to those waves which will be produced by radiating waves of 550,000, 540,000 cycles, etc., together with 500,000 from a system such as shown in Fig. 5 and detecting 30 them by means of a detector 23. The auxiliary carrier frequency waves are seen to have frequencies higher than the frequencies essential to the accurate reproduction of articulate speech. The auxiliary local source 35 27 is not shown in Fig. 7 since it is entirely unnecessary for selective reception of the several signals so long as a wave having a frequency of 500,000 cycles is being received from a system such as shown in Fig. 5 or 40 from some other system.

Fig. 8 illustrates a group of transmitting stations 28, 29, 30, 31 and 32 each arranged to transmit a different modulated signal wave $q \pm s$, $q_1 \pm s_1$, etc. The frequency q 45 may be 550,000 cycles, q' , 540,000, etc. Stations 33, 34, 35, 36 and 37 represent a group of receiving stations at each of which it is desired to receive one of the signals sent out 50 from the transmitting stations without interference by any of the others. This is accomplished by sending from stations 28 or from any other suitable source a wave p having a frequency of 500,000 cycles. If the stations 33, 34, etc., are like that illustrated 55 in Fig. 7, each station will be enabled to selectively receive the message being transmitted from any of the stations 28, 29, etc. Furthermore, it will be possible for each station 33, 34, etc., to simultaneously receive, if desired, the messages being sent out from stations 28, 29, etc. It is unnecessary to have a local 60 source at any of the receiving stations and it is necessary to have only one source of waves of frequency p at one of the transmitting stations. This source may, if desired, be at

some other station which is not engaged in transmission. The interfering waves which would be due to modulation of the carrier wave of frequency p by harmonics of waves of the auxiliary frequencies q , q_1 , etc., are 70 eliminated. Furthermore it will be seen by reference to Fig. 1 that where a plural modulation system of the ordinary type transmits waves both above and below any carrier frequency p , the system herein described 75 will produce equally efficient waves, thereby leaving free the remainder of the wave lengths for the transmission of other messages between other signaling stations.

The novel features believed to be inherent 80 in the invention are defined in the appended claims.

What is claimed is:

1. The method of multiplex signaling which comprises transmitting a plurality of 85 carrier waves, each modulated in accordance with speech, which carrier waves have frequencies differing too slightly to be efficiently selected at a receiving system and transmitting along with said waves a wave 90 of a frequency differing from any thereof and combining said wave with each of said carrier waves in order to produce at a receiving system speech modulated waves of 95 such characteristics as to be readily separated.

2. The method of separately receiving a plurality of radiated waves, all but one of 100 which are modulated in accordance with a signal wave, which comprises producing at a receiver the difference frequencies between each of said modulated waves and said one wave, selecting the difference frequencies, and separately detecting the selected waves to produce the signal wave according to 105 which the corresponding modulated wave is modulated.

3. The method of multiplex signaling which comprises transmitting a plurality of 110 waves each modulated by a signal wave and simultaneously transmitting a base frequency wave, causing said modulated waves to interact at a receiver with said base frequency wave to produce auxiliary frequency waves of frequencies above the highest range 115 of frequencies necessary for the production of audible speech, and in separately detecting the auxiliary frequency waves.

4. The method of telephone communication between two widely separated stations 120 which comprises utilizing at one station a wave transmitted from a second station widely separated from the first station to selectively receive a speech wave transmitted from a third station.

5. The method of telephone communication which comprises transmitting high frequency speech modulated waves from each of two stations and transmitting from one of said stations a wave enabling said waves 130

to be separated at a cooperating receiving station.

6. A transmission system comprising means for producing, modulating in accordance with individual sound signals and transmitting each of a plurality of waves, and means for producing and transmitting therewith a wave of a frequency enabling each one of said waves to be separated from the others at a receiving station to reproduce the modulating sound.

7. A system comprising means for producing, modifying in accordance with individual signals and transmitting a series of waves of frequencies q , q_1 , and q_2 , etc., and means for producing and transmitting a wave of frequency p , in combination with receiving means adapted to receive said waves and produce therefrom waves of frequencies $p-q$, $p-q_1$, $p-q_2$, etc., at least one of said produced waves being of superaudible frequency, and means for deriving and separately indicating the individual signals from each of said last mentioned waves.

25 8. A system comprising a plurality of transmitting stations and a plurality of receiving stations, means for transmitting a carrier wave modulated in accordance with a signal wave from each of said transmitting stations, means for transmitting from a single source an unmodulated wave, and means at each of said receiving stations for combining energy derived from said unmodulated wave with energy derived from said modulated waves in order to selectively receive the signal carried by one of said modulated waves.

9. A multiplex communication system comprising means for transmitting through 40 the same medium a series of carrier waves differing in frequency by a slight percentage of the frequency of the lowest thereof, means for transmitting another wave, means at a receiving station for combining said series 45 of waves with energy of said other wave and producing a corresponding series of carrier waves whose frequencies differ by a relatively great percentage of the frequency of the lowest thereof, electrical selecting means for selecting such of said last mentioned waves as are desired to be received at said receiving station, and means for deriving signals therefrom.

50 10. A carrier wave transmitting system comprising means for transmitting an unmodulated wave and means for transmitting therewith either a signal modulated wave having a carrier frequency greater than said first mentioned wave by a given amount or a wave having a carrier frequency less than said first mentioned wave by said given amount, said means being capable of changing the modulated wave from one frequency to the other without interruption of signaling or the transmission

of any waves other than the frequencies stated.

11. A system for signaling comprising two sources of high frequency waves differing by a frequency above good audibility, 70 means for modulating the wave from one of said sources in accordance with a signal wave to produce a modulated wave of the same carrier frequency as the unmodulated wave, a common means for transferring the energy of the modulated and unmodulated waves to a transmitting conductor for transmission to a distant point, and channels for transferring said modulated and unmodulated waves to said common means, said channels each including elements rendering them selective of one of said waves to the exclusion of other waves.

12. A system in accordance with claim 11 in which the common means comprises an 80 amplifier for increasing the energy of the waves before transmission.

13. A system for signaling comprising two sources of high frequency waves differing by a frequency above good audibility, 90 means for modulating the waves from both of said sources in accordance with the same signal wave to produce modulated waves, a common means for transferring the energy of the modulated waves to a transmitting 95 conductor for transmission, and channels for transferring said modulated waves to said common means, said channels including elements rendering them selective of one of said waves to the exclusion of other waves.

14. A system in accordance with claim 13 in which the common means comprises an amplifier for increasing the energy of the waves before transmission.

15. A system for signaling comprising a 105 plurality of sources of high frequency waves differing by a frequency of at least 2,000 cycles per second, means for modulating the waves from each of said sources in accordance with individual signal waves 110 of audible frequencies to produce modulated waves of the same carrier frequency as the unmodulated waves, a common means for increasing the energy of the modulated waves before impressing them upon a transmitting conductor for transmission to a distant point, and channels for transferring said modulated and unmodulated waves to said common means.

16. A system in accordance with claim 15 120 characterized by the inclusion in said channels of elements rendering said channels selective of the modulated wave to be transferred thereto to the exclusion of other undesired waves.

17. In a signaling system for transmitting two waves of different frequencies modulated in accordance with the same signal, arrangements for providing wave energy of the two frequencies, and a constant 130

- current modulating system for varying the amplitudes of the two waves in accordance with the signal, in combination with means for transmitting the energy of the modulated waves. 5
18. A signaling system for producing and transmitting from a single station a plurality of carrier waves of different frequencies, means for modulating said carrier waves, means for transmitting from the same station a wave of frequency adapted to be used at a receiving station to separate and distinguish between said carrier waves, and means serving in common for 10 the production or transmission of more than one of said waves. 60
19. The method of separating and selectively receiving a desired one of several effects simultaneously transmitted on high frequency carrier waves differing by an amount above audibility but less than will enable their direct separation by selective apparatus which comprises transmitting from a station remote from the places of reception and transmission energy of a definite wave frequency, combining at the place where any one of the effects is to be received energy of the definite wave frequency with the energy corresponding to the effect to be received, segregating a resultant energy inherently containing the effect to be produced from other resultant energies inherently containing undesired effects, and producing the desired effect from the selected energy. 65
20. The method of transmission which comprises generating and transmitting a signal modulated carrier wave and generating and transmitting a wave differing therefrom in frequency by an amount above the range of frequencies used for the reproduction of audible speech, receiving said modulated and unmodulated waves at a receiving station and combining them to produce a combination frequency wave, separating the combination frequency wave from other waves by electrically selective means, and converting the selected wave to reproduce the signal. 70
21. The method of transmission and reception which comprises generating and modifying a high frequency wave, transmitting said wave to a distant point, generating and transmitting with said wave another wave differing therefrom in frequency by an amount greater than 2,000 cycles per second, receiving both of said waves at a receiving station and combining their energies to produce a combination frequency wave, electrically selecting said combination frequency wave to separate it from other waves, and distorting said selected wave to produce indications corresponding to the modification of the modified wave transmitted. 75
22. A system of communication comprising a transmitting station having means for generating and transmitting two waves of different frequencies, and a receiving system for receiving said waves, said receiving system comprising a device for combining said waves to produce a combination frequency wave, means for selecting said combination frequency wave, and distorting means for converting the frequency of said combination frequency wave. 80
23. A system of transmission comprising a transmitting station having means for generating and transmitting two waves of different frequencies together with means for modifying both of said waves by indications to be transmitted, and a receiving system, said receiving system comprising a device for combining said waves to produce a combination frequency wave, means for selecting said combination frequency wave from other waves, and distorting means for converting said combination frequency wave to produce the indications. 85
24. In a system for selective transmission and reception, apparatus for producing, and a channel for transmitting, a high frequency wave modified in accordance with indications to be reproduced at a receiver, means for producing another wave, means comprising a channel—other than the channel for transmitting the modified wave—for transmitting in unmodified form energy of the second wave, a receiving station adapted to receive and combine the energy of the modified and unmodified waves to produce waves having a frequency above the usual range of frequencies of audible sounds, and means for utilizing said produced waves to reproduce indications corresponding to the modifications of the modified transmitted wave. 90
- 50 55 60 65 70 75 80 85 90 95 100 105

In witness whereof, I hereunto subscribe my name this 27th day of September A. D., 1919.

RAYMOND A. HEISING.
